Primary Examiner — Selina Sikder(74) *Attorney, Agent, or Firm* — Kolisch Hartwell, P.C.(57) **CLAIM**

We claim the ornamental design for a home automation control device, as shown and described.

DESCRIPTION

FIG. 1 is an isometric view of the design.

FIG. 2 is a front view of the design.

FIG. 3 is a back view of the design, wherein features of the home automation control device shown in broken lines are to provide perspective of the environment, and form no part of the claimed design.

FIG. 4 is a top view of the design.

FIG. 5 is a bottom view of the design.

FIG. 6 is a left side view of the design.

FIG. 7 is a right side view of the design; and,

FIG. 8 is an isometric view of the design, wherein features of the home automation control device shown in broken lines are to provide perspective of the environment, and form no part of the claimed design.

1 Claim, 8 Drawing Sheets(56)
